CLAIM

The ornamental design for a handbag with convertible strap, as shown and described.

DESCRIPTION

FIG. 1 is a top, front, right side perspective view of a handbag with convertible strap showing my new design;

FIG. 2 is a top plan view thereof;

FIG. 3 is a rear elevational view thereof with the strap in a disconnected condition;

FIG. 4 is a left side elevational view thereof;

FIG. 5 is a bottom plan view thereof;

FIG. 6 is a cross-sectional view thereof taken along line 6—6 of FIG. 1;

FIG. 7 is a front elevational view thereof;

FIG. 8 is a front elevational view thereof, the strap shown in a modified condition; and

FIG. 9 is a front elevational view thereof, the strap shown in a modified condition.

FIG. 1.

FIG. 2.

FIG. 3.

FIG. 4.

FIG. 5.

FIG. 7.

FIG. 8.

FIG. 9.

FIG. 6.
